UNITED STATES PATENT OFFICE

2,254,732

TONE ARM

Roy Dally, Racine, Wis., assignor to Webster Electric Company, Racine, Wis., a corporation of Delaware

Application April 29, 1940, Serial No. 332,202

7 Claims. (Cl. 274—1)

The present invention relates to tone arms and is particularly concerned with improved constructions of the tone arm and the supporting arrangements whereby the tone arm is secured to a fixed support for engagement with a record on a turntable.

One of the objects of the invention is the provision of an improved tone arm adapted to be used for sound reproduction apparatus of high fidelity, which is adapted to be used with conventional phonographs, and to give the best reproduction and minimum record wear, and to eliminate undesirable frequency responses.

Another object of the invention is the provision of an improved light tone arm structure, having a minimum amount of friction and inertia about a vertical axis, and adapted to facilitate high fidelity reproduction.

Another object of the invention is the provision of an improved tone arm pivotal support by means of which the tone arm may be so mounted that it can be lifted up, when installed on the phonograph, to such a position that the bottom of the pickup can be inspected and the needle can be most conveniently inserted.

Another object of the invention is the provision of an improved tone arm support having a resilient connection between the tone arm and the support so that the tone arm can be removed at any time by merely springing apart the bearing springs which are carried by one of these parts.

Another object of the invention is the provision of an improved tone arm supporting structure by means of which undesirable vibrational characteristics of the tone arm or needle noise may be absorbed to prevent the transmission of undesirable vibrations to the stylus of the needle and the pickup device carried by the tone arm.

Another object of the invention is the provision of an improved construction for supporting a tone arm, by means of which the tone arm is permitted to vibrate as a unit, thus reducing the resonant frequency characteristics which are present whenever an arm vibrates in torsion.

Other objects and advantages of the invention will be apparent from the following description and the accompanying drawing in which similar characters of reference indicate the same parts throughout the several views.

Referring to the single sheet of drawings accompanying this specification:

Fig. 1 is a fragmentary plan view of a phonograph installation showing the relation of the tone arm and the record on the turntable;

Fig. 2 is a full size vertical sectional view taken on the plane of the line 2—2 of Fig. 1 looking in the direction of the arrows, partially broken away to show the interior structure of the tone arm support;

Fig. 3 is another fragmentary vertical sectional view taken on the plane of the line 3—3 of Fig. 2 looking in the direction of the arrows; and

Fig. 4 is a fragmentary horizontal sectional view taken on the plane of the line 4—4 of Fig. 2.

Referring to Figs. 1 and 2, 10 indicates the supporting structure of a phonograph which is provided with the usual turntable indicated at 11 carrying the phonograph record disc 12. 13 indicates a tone arm constructed according to the present invention and supported upon the base 10 for substantially universal pivotal movement, in order that it may be raised from or lowered to the record and in order that it may move horizontally across the face of the record as the playing of the record progresses. The base 10 is preferably provided with a special tone arm support 14 located at one side of the turntable 11 and adapted to support the tone arm 13 with its needle out of contact with the base 10. This support may consist of a sheet metal member having the horizontal attaching flange 15 secured to the wooden base 10 by means of a wooden screw 16 and having a vertically extending column 17. The top of the column 17 is provided with a substantially V-shaped notch 18 adapted to receive the stem 19 of a headed member 20 carried by the side of the tone arm.

The headed member 20 has its stem 19 provided with riveted formations inside and outside the adjacent wall 21 of the tone arm 13. The supporting post 22 for the tone arm is preferably so located with respect to the stylus 23 and with respect to the direction in which the stylus 23 points, that there is substantially tangential tracking of the needle in the groove on the record. This of course can only be approximated as the angle of the stylus varies from the outermost groove to the innermost groove and exact tangential tracking can only be attained for one predetermined groove location.

The supporting post 22 may consist of a cast metal tubular member of substantially cylindrical form provided with a cylindrical through-bore 25 axially located in the post. The upper end of the post may be provided with a curved tapered surface 26 and the inner end of the bore 25 may be chamfered at 27, leaving only an annular thrust surface 28 of reduced area for permitting rotation with a minimum amount of friction.

The lower end of the post 22 is preferably of reduced diameter and threaded at 29, leaving an annular shoulder 30 for engagement with a washer or thrust plate 31. The post 22 may be secured to the wooden base 10 by means of another washer 32 and a nut 33 which clamps the board 10 between the washers 31 and 32. The supporting post 22 rotatably supports a hollow shaft 35 which comprises a cylindrical tubular brass member, the bore of which is utilized to pass the conductors 36 and 37 which lead to the pickup unit 38.

Tubular shaft 35 may be provided at its lower end with an annular groove 40 (Fig. 3) of substantially semi-circular cross-section adapted to receive the spring wire 41 which fits in the groove 40 and forms a thrust bearing for the lower end of the shaft 35 to retain the shaft in the post 22. That part of the spring wire 41 which projects from the groove 40 engages the annular thrust surface 42 on the lower end of the post 22 when the shaft 35 is actually subjected to any lifting force. As a matter of actual practice, this would only occur when the phonograph were turned upside down or subjected to unusual movements and thus the tone arm customarily rests upon the thrust surface 28 and the wire 41 serves the purpose of maintaining the parts in permanent assembly.

The upper end of the tubular shaft 35 is preferably subjected to an upsetting operation which produces an annular rib 45 having the upper and lower substantially flat surfaces 46 and 47. The surface 46 serves as a thrust bearing engaging the bearing surface 28 on the post 22. The tubular shaft 35 is also preferably formed with a partially spherical protuberance 48 immediately above the flange 45 and after assembly with the cushion member 49, it is also formed with an outwardly spun flange 50 outside a metallic washer 51. The cushion member 49 preferably consists of a soft resilient annular member having, before its assembly with the parts of Figure 3, a cylindrical through-bore 55. It also has the substantially flat end surfaces 56 and 57 and its outer surface may be substantially circular in cross-section at 58, 59. The annular cushion member 49 is provided with an annular groove 60 of substantially rectangular cross-section located in its periphery midway between the ends 56, 57, and adapted to receive the adjacent parts of a metal pintle plate 61.

The pintle plate 61 is shown in Figure 4 and Figure 2. It comprises a relatively thick sheet metal member, the main body of which is substantially rectangular in shape, being provided with the substantially straight edges 62, 63 and with a substantially circular end boundary 64. At its opposite end, it tapers inward at 65 and 66 and the relatively narrow end portion 67 is bent upward at 68. The extreme end 69 of this pintle plate is adapted to serve as a stop for engaging inside the upper wall 70 of the tone arm 13 to prevent the stylus 23 from engaging the base 10 when the tone arm is at one side of the record. This is, of course, also prevented by the supporting column 17 when the tone arm is on the supporting column.

The pintle plate 61 has at one end (the right end in Figure 4) a circular aperture 71 which is slightly smaller than the diameter of the base 72 of the groove 60 in the cushion member 49. The thickness of the plate 61 is substantially the same as the width of the groove 60.

Thus, the cushion member 49 may be placed 75

inside the aperture 71 in such manner that its flanges 73 and 74 are located below and above the pintle plate 61. The cushion member 49 and the pintle plate 61 may then be placed upon the partially spherical formation 48 of the tubular shaft 35 and secured in place by means of the washer 51 which is held in place by the spun formation 50. The space between the washer 51 and the flange 45 is such that the cushion member 49 is placed under a predetermined compression so that the pintle plate is resiliently gripped by the cushion member 49 and the cushion member 49 also resiliently grips the partially spherical formation 48 on the shaft 35. The relation of all the parts surrounding the cushion member 49 is such that the cushion is placed under compression and the pintle is resiliently supported upon the shaft 35 but out of all metallic contact with the shaft.

The pintle plate 61 is provided with a pair of laterally projecting portions 76, 77 which are also subjected to an upsetting operation for the purpose of forming the substantially frusto-conical pintle surfaces 78. These pintle surfaces bear such a relation to the bearing apertures 79, one of which is located in each wall 21 or 80 of the tone arm, that each aperture receives one of the pintles 76, 77.

The cushion member 49 also supports the tone arm in such manner that it is permitted to vibrate as a unit. This reduces the resonant frequency characteristics of the tone arm which are present whenever a tone arm is vibrated in torsion.

The size of the apertures 79 is such that the inner edge of each aperture engages on the frusto-conical wall 78 of the pintles 76, 77. The length of the pintle plate 61 axially of the pintles 76, 77 is such that the side walls 21 and 80 of the tone arm are placed under predetermined tension when the parts are in the position of Figure 3. Furthermore, the two walls 21 and 80 may be forced apart to permit the removal of the pintle plate 61 by producing a disengagement of one or the other of the pintles 77 from its aperture 79. Thus the tone arm is removable from the vertical shaft 35 at all times. The frusto-conical pintles are adapted to have an annular line contact with the apertures 79 in the tone arm so that they permit movement in a vertical plane with a minimum amount of friction.

The tone arm 13 preferably consists of a stamped sheet metal member of channeled form provided with an integral top wall 70 and a pair of parallel side walls 21 and 80. The side walls 21 and 80 are joined by an integral end wall 81 (at the right in Figure 2) and with an integral end wall 82 (at the left end in Figure 2). Referring to Figure 1, the tone arm 13 is preferably provided with a channeled formation 83 extending diagonally backward from the end 82 and terminating in an end wall 84. This channeled formation is for the purpose of receiving and locating a crystal reproducer unit 85 of the type shown in my prior application, Patent No. 2,197,967, issued April 23, 1940, Sound reproducing apparatus, and indicated at 145 in Fig. 8 of that patent, at such an angle to the main body of the tone arm 13 that substantially tangential tracking may be secured. The present tone arm may, however, be used with any type of reproducer unit such as electro-magnetic reproducer units or crystal reproducer units. The crystal unit may be secured in place by means of a pair

of angle brackets, one angle bracket 86 being spot-welded to the top wall 70 of the tone arm and having a downwardly extending flange 87 and a horizontally extending flange 88. Another similar angle bracket may have a horizontal flange 89 secured to the flange 88, a side flange 90, and a horizontal clamping flange 91 which engages the crystal unit 85 and holds it in the tone arm when the flanges 88, 89 are secured together.

The conductors 36 and 37 are secured in the channeled tone arm 13 by their attachment at one end to the crystal unit 85 and at the other end by passing into the hollow shaft 35. In between these points there may be spot-welded bendable metal clips 92 which may engage and support the conductors 36 and 37. The circuit preferably includes a signal light indicating when the circuit is energized and the light may be exposed through an aperture in the tone arm 13 which is covered with a transparent button 93 of a phenolic condensation composition.

The cushion member 49 is preferably made of pure para rubber of soft resilient characteristics or it may be made up out of printer's roll composition peculiarly adapted to prevent the transmission of undesirable vibrations from the support 10 to the tone arm 13. The tone arm 13 itself may also be molded out of phenolic condensation compounds, if desired.

It will thus be observed that I have invented an improved tone arm which is light in weight and adapted to prevent undue wear upon the records. Due to the location of its pintles and specific construction of the arm, the arm may be lifted high enough so that the needle aperture may be inspected and the needle most conveniently inserted. The arm supporting structure is simple and adapted to take up wear and to prevent rattling and there is a complete absence of metal-to-metal contact between the tone arm and its metallic supporting post carried by the base of the phonograph or other device.

While I have illustrated a preferred embodiment of my invention, many modifications may be made without departing from the spirit of the invention, and I do not wish to be limited to the precise details of construction set forth, but desire to avail myself of all changes within the scope of the appended claims.

Having thus described my invention, what I claim as new and desire to secure by Letters Patent of the United States is:

1. In a tone arm, the combination of a support with a bearing member extending transversely to said support, a shaft rotatably mounted in said bearing member and having means at each end retaining it in said bearing member, a resilient cushion member carried by said shaft, a pintle plate carried by said cushion member and having oppositely extending trunnions, and a tone arm having bearings engaging said trunnions, whereby said tone arm is supported for substantially universal movement on said support, said cushion member absorbing and preventing transmission of undesirable vibrations from said support to said tone arm, a pair of annular compression members carried by said shaft, said cushion member comprising a soft, resilient, annular rubber member compressed between said two annular compression members on said shaft.

2. In a tone arm, the combination of a support with a bearing member extending transversely

to said support, a shaft rotatably mounted in said bearing member and having means at each end retaining it in said bearing member, a resilient cushion member carried by said shaft, a pintle plate carried by said cushion member and having oppositely extending trunnions, and a tone arm having bearings engaging said trunnions, whereby said tone arm is supported for substantially universal movement on said support, said cushion member absorbing and preventing transmission of undesirable vibrations from said support to said tone arm, a pair of annular compression members carried by said shaft, said cushion member comprising a soft, resilient, annular rubber member compressed between said two annular compression members on said shaft and having a peripherally located annular groove for receiving the adjacent parts of said pintle plate.

3. In a tone arm, the combination of a support with a metallic bearing member having a cylindrical bore and a reduced threaded cylindrical portion with thrust members carried at each end of said threaded portion and threaded means whereby the bearing may be clamped on the support, a tubular shaft member rotatably mounted in said cylindrical bore in said bearing, removable means at one end of said shaft for retaining it in said bearing, an annular flange carried by said shaft at the other end of said bearing, said bearing having a reduced annular thrust surface engaging said flange, a thrust member, a resilient rubber cushion member of annular shape clamped between said flange and said thrust member carried by the end of said shaft, a pintle plate carried by said cushion member, and a tone arm carried by said pintle plate for pivotal movement, said cushion member having an annular groove formed in its periphery and said pintle plate having an aperture of a size adapted to receive that portion of the cushion member at the base of said groove.

4. In a tone arm, the combination of a support with a metallic bearing member having a cylindrical bore and a reduced threaded cylindrical portion with thrust members carried at each end of said threaded portion and threaded means whereby the bearing may be clamped on the support, a tubular shaft member rotatably mounted in said cylindrical bore in said bearing, removable means at one end of said shaft for retaining it in said bearing, an annular flange carried by said shaft at the other end of said bearing, said bearing having a reduced annular thrust surface engaging said flange, a thrust member, a resilient rubber cushion member of annular shape clamped between said flange and said thrust member carried by the end of said shaft, a pintle plate carried by said cushion member, and a tone arm carried by said pintle plate for pivotal movement, said cushion member having an annular groove formed in its periphery and said pintle plate having an aperture of a size adapted to receive that portion of the cushion member at the base of said groove, said cushion member being subjected to a predetermined compression for the purpose of preventing transmission of predetermined vibrations from said bearing to said tone arm.

5. A mounting for tone arms comprising a tubular metal member having an axially extending through bore, said tubular metal member being formed on one end with an annular shoulder and a reduced threaded portion, threaded means carried by said reduced threaded portion for clamping the said tubular metal member on a support,

said tubular metal member having thrust bearing surfaces at each of its ends, a tubular shaft rotatably mounted in said through bore and having means at its lower end for engaging the adjacent thrust surface on said tubular metal member, said tubular metal shaft having an annular thrust flange projecting at substantially right angles to its axis and located at the upper end of said tubular metal member, a live resilient rubber bushing member carried by the upper end of said tubular shaft and having an annular groove located in its periphery, a compression member carried above said cushion member, said tubular shaft being spun outwardly to retain said compression member, and a pintle plate located in said annular groove, said pintle plate having oppositely projecting pintles with frusto-conical bearing surfaces located thereon, said live resilient cushion member being placed under a predetermined state of compression between said thrust flange and said compression member whereby the pintle plate is resiliently clamped between the walls of said groove.

6. A mounting for tone arms comprising a tubular metal member having an axially extending through bore, said tubular metal member being formed on one end with an annular shoulder and a reduced threaded portion, threaded means carried by said reduced threaded portion for clamping the said tubular metal member on a support, said tubular metal member having thrust bearing surfaces at each of its ends, a tubular shaft rotatably mounted in said through bore and having means at its lower end for engaging the adjacent thrust surface on said tubular metal member, said tubular metal shaft having an annular thrust flange projecting at substantially right angles to its axis and located at the upper end of said tubular metal member, a live resilient

rubber bushing member carried by the upper end of said tubular shaft and having an annular groove located in its periphery, a compression member carried above said cushion member, said tubular shaft being spun outwardly to retain said compression member, and a pintle plate located in said annular groove, said pintle plate having oppositely projecting pintles with frusto-conical bearing surfaces located thereon, said live resilient cushion member being placed under a predetermined state of compression between said thrust flange and said compression member whereby the pintle plate is resiliently clamped between the walls of said groove.

5 7. In a tone arm, the combination of a supporting post with a shaft rotatably mounted in said shaft, said shaft having laterally projecting and oppositely disposed trunnions carried by its upper end and a channelled tone arm, said tone arm having downwardly projecting flanges on each side, said flanges being provided adjacent one end of the tone arm with apertures for receiving said trunnions, and said tone arm being formed at its free end with a diagonally extending housing portion, and a reproducer member located in said diagonally extending housing portion, said housing portion and reproducer being arranged at such an angle that there is substantially tangential tracking of the needle carried by the reproducer in the grooves of the record substantially midway between the beginning and end groove of the record.

ROY DALLY.
